UNITED STATES PATENT OFFICE.

RAESFELD JEANNE DE GERSON, BORN BERTHIER, OF PARIS, FRANCE.

PROCESS FOR THE MANUFACTURE OF ARTIFICIAL FLOWERS.

Application filed October 12, 1925, Serial No. 62,163, and in Germany August 5, 1925.

Artificial flowers are usually constituted by assemblage, by means of glue for instance, of petals obtained by cutting out or with a hollow punch, and final conformation of 5 paper, fabric, etc. When the petals are assembled on the cup or calyx for forming the corolla, they give the representation of a bud, of a half-blown or blown flower, but it is not possible to modify the shape of these 10 petals once constituted so as to transform, for instance, a blown flower into a bud, or reversely.

The present invention has for its object a process for the manufacture of artificial 15 flowers which, on the one hand, allows to obtain new imitations of the natural flower, on the other hand, permits to remedy the above mentioned inconveniences, in that the petals can be modified, after the constitution of the 20 flower, so as to alter at will the appearance of the same. This process essentially consists in fixing one by one, by stitches, petals formed in a ribbon, preferably continuous, on a central mould constituted by a casing 25 enclosing a pulverulent substance, the conformation of these petals being such that it is possible to modify at will the respective configuration and the relative arrangements.

In the accompanying drawing and by way 30 of example:

Fig. 1 is a perspective view of the central metal armature.

Fig. 2 is a vertical section of the mould on which the petals are mounted.

Fig. 3 is a perspective view of the mould and of its metal armature.

Fig. 4 shows a portion of ribbon intended for forming a petal of the flower.

Figs. 5 and 6 illustrate in front view and 40 side view the petal obtained by the conformation of the ribbon of Fig. 4.

Figs. 7 and 8 are corresponding views of the petal of Figs. 5 and 6 presenting another configuration.

For constituting a flower, in accordance 45 with the features of the present invention, a central mould is first formed. This mould is constituted by a metal armature forming a ring 1. In practice, this armature is constituted by a brass wire which is conformed in the shape of a ring 1 and is twisted at 2, so as to obtain two parallel branches 3. On the ring 1 is secured, by sewing, a bottom 3^a, 50 made of fabric, and having the shape of a

cup (Fig. 2). With a fabric (muslin for instance) a pocket 4 is formed and filled with a pulverulent material 5, perfumed or not. This pocket 4 is tied up so as to close it and it is introduced in the cup 3 formed by the fabric. This pocket 4 is sewn on the ring 1. A kind of plastic ball is thus constituted, which pushes the fabric 3 outwardly and holds it in a stretched condition. One of the branches 3 of the armature can be curved for straddling this ball (Fig. 3) and can be 60 twisted at 6 with the other branch. The whole constitutes the support of the stem of the flower, which stem is made in the ordinary manner.

The mould or ball thus obtained is adapted 70 to receive and retain the threads which permit to assemble thereto, by stitches, the petals produced as described hereinafter.

The petals of a flower are respectively constituted by pieces of ribbon (satin for instance) (Fig. 4) or by the parts of a continuous ribbon. The ends 7—8 of one of the selvages are assembled together after having curved this selvage (Fig. 5). The ends 9—10 of the ribbon and the other selvage 80 11 are plaited so that they can be assembled on the seam of the ends 7—8 of the selvage. A plaited petal in the shape of a cup is thus obtained as shown in Figs. 5—6. The petals are assembled in concentric rows 85 on the central ball, the pulverulent material 5 contained in the said ball, permitting the passage of the assembling threads, whatever may be the places where the needle enters. This pulverulent material immobilizes the 90 sewing threads, by giving them a sufficient freedom for permitting to modify the shape of the petals and it maintains the central support in shape. It is obvious that according to the physiognomy of the flower it is desired to imitate, it is possible, by choosing different lengths of ribbon, to obtain petals having different shapes and dimensions; these petals cannot unravel since their edges are constituted by one of the selvages 7—8 100 of the ribbon.

Flowers are thus obtained in which the petals have not an unchanging configuration. In fact, it is possible to rumple the whole, to lengthen the petals (Figs. 7 and 8), to engage 105 the petals in each other for forming a bud or a half-blown flower, that is to say to modify at will the physiognomy of the artificial

flower, which is impossible with the products made by the actually known manufacturing processes.

The flowers thus obtained present also the following advantage: It is possible to clean them by dipping them in a suitable liquid bath (spirit, benzine, etc.,) without this causing them to lose their shapes, whilst on the contrary, flowers made in the ordinary manner, lose their dressing and unglue if they are subjected to a treatment of this kind.

What I claim and desire to secure by Letters Patent is:

1. In an artificial flower, a central pocket of lenticular shape, a powder within the said pocket for permitting the passage of the assembling threads for the petals, an armature constituted by a wire forming a circular handle and two unequal parallel branches, and means for securing the said pocket in the circular handle of the armature.

2. In an artificial flower, a central lenticular pocket containing a powder, an armature constituted by a wire forming a circular handle and two unequal branches, a fabric sewn on the circular handle so as to form a cup which receives the central lenticular pocket, one of the branches of the armature being bent, then twisted on the other branch for straddling the central pocket and holding it in position.

3. In an artificial flower, a central lenticular pocket containing a powder, a metal armature for holding the said pocket and form-

ing the tail of the flower, petals made of ribbon and secured by threads passing through the central pocket.

4. In an artificial flower, a central lenticular pocket containing a powder, a metal armature for holding the said pocket and forming the tail of the flower, petals constituted by rectangular pieces of ribbon the ends of a selvage of which are connected by sewing with the other selvage centrally plaited, these petals being assembled by threads passing through the central pocket.

5. In an artificial flower, a central lenticular pocket, a powder in the said pocket, an armature constituted by a wire forming a circular handle and unequal branches which constitute the stem of the flower, a fabric sewn on the edge of the circular handle so as to form a cup which receives the central lenticular pocket, one of the branches of the armature being bent and twisted on the other branch for straddling the central pocket and holding it in position, petals constituted by rectangular pieces of ribbon the ends of a selvage of which are assembled together by sewing and with the opposite selvage which is centrally plaited, threads passing through the base of the petals and the central lenticular pocket for obtaining the assemblage of the said petals.

In testimony whereof I have signed my name to this specification.

RAESFELD JEANNE DE GERSON,
BORN BERTHIER.
